ATTORNEY

Patented May 1, 1928.

UNITED STATES PATENT OFFICE.

RICHARD H. BELL, OF SANTA CLARA, CALIFORNIA.

RADIOSIGNALING.

Application filed December 27, 1923. Serial No. 682,972.

It is the object of the invention to provide a simple, practical and highly efficient method and means of controlling the electrical impulses set up in wireless telephony or teletypography whereby to render a sending or receiving apparatus highly selective as to wave length and delicately adjustable as to amplification, and one that will also increase the resonance and clearness of signals.

10 In the drawing:

Figure 1 is a diagrammatical illustration of a receiving set embodying my invention.

Figure 2 is a diagrammatical illustration of another embodiment of my invention.

15 Figure 3 is a diagrammatical illustration of still another embodiment of the invention.

Figure 4 is a diagrammatical illustration of another embodiment of the invention.

20 In carrying out my invention in what is perhaps the simplest form in a wireless receiving set, I provide a simple vacuum tube non-regenerative receiving set indicated generally by the numeral 1, all the parts represented being situated in and belonging to the set.

At 2 I show the aerial grounded at 3 through the primary winding 4 of the coupler in the set, the slider being indicated at 4^a and the aerial and ground terminals of the set being indicated at 5 and 6 respectively.

30 In the primary winding 4 is slidably inserted a secondary winding 7, having no metallic connections with any part of the circuit of aerial or set. This secondary coil 7, in other words, is situated in the primary coil 4 with simply an air space between the two elements.

40 When the set is in operation, a movement of the secondary coil longitudinally or otherwise, but always so as to cut through the lines of magnetic force emanating from the primary coil, influences the electrical impulses 45 passing through the primary coil in such a manner as to not only amplify the signals but to also accurately and delicately control the wave length, serving as an adjustment supplementary to the usual control on the primary coil and such other devices as may be inserted in either the aerial or set circuits.

50 In Figure 2 a variation of this structure is shown in which a metallic mass 8 (preferably copper in hollow cylindrical form) is used as a secondary and operated in a man-

ner similar to coil 7 and by means of which similar results are obtained.

In Figure 3 a combination is shown in which both a secondary coil 9 and a secondary mass 10 are used, and either one or the other operated as desired.

Another embodiment of the invention is shown in Figure 4, wherein two secondary elements 11 and 12 are used in conjunction with primary coil 4, the end 13 of the secondary coil 12 being connected to the ground terminal 6 of the set, and one of the primary terminals as 14, connected to the terminal 5 of the set. In this form one end of the primary coil as 15 is left open and contact made with the aerial 2 by the slider 4^a. Also one end of the secondary 12, as at 16, is left open. This arrangement permits, perhaps, even finer adjustment than the forms before disclosed since different adjustments may be made relative to the one primary coil. Attention is particularly called to the fact that one end of the secondary coil is grounded together with the other part of the circuit, but the other end of the secondary being free and one end of the primary being free there results an open circuit between 4 and 12 and this is used in combination with element 11 or not as desired.

55 The successful operation of this invention depends apparently upon the reaction of the electrical currents flowing through the primary coil upon the secondary element, and consequently it is immaterial whether or not the said secondary be placed within the primary or not. It is only necessary that the secondary be an open circuited coil or a mass of some suitable metallic substance arranged in proximity to the primary coil and movable lengthwise with relation thereto or in such a manner as to cut through the lines of magnetic force of the primary.

60 The action between the primary and secondary is similar to the action of a choke-coil used in alternating circuits but instead of an iron core copper, brass, silver or gold, or a coil made of any of these metals is preferably used. However, it is not exactly the same for the effect is seen also in incomplete or open circuits as shown in Figure 4. Iron 100 might also be used or any other metal, simple or composite, but the action does not appear to be as good.

65 The reaction obtained by arranging the secondary in suitable relation to the primary 110

and metallically disconnected therefrom, or if connected metallically so connected as to not form even a complete circuit, inductively considered with relation to the remaining 5 part of the circuit, secures to the set a musical volume and musical resonance not ordinarily obtained with the so-called regenerative hook-up, but which however may be applied to regenerative sets with im-
proved results.

The above principle may evidently be applied to aerial circuits alone and used in conjunction with any receiving or sending set whatever.

15 It is to be understood, of course, that while I have herein shown and described certain forms of the invention, changes in form, construction, and method of operation may be made within the scope of the appended
20 claims.

I claim:—

1. In a radio receiving circuit having an aerial and a detector circuit including a

three electrode tube, a primary coil having one end connected to the input of said tube 2 and having its opposite end open, a secondary coil inductively coupled to said primary coil and having one end connected to the grounded filament circuit of the tube and having its opposite end open, and means 30 for adjustably connecting said aerial to the primary coil.

2. In a radio receiving circuit having an aerial and a detector circuit including a three electrode tube, a primary coil having 35 one end connected to the input of said tube and having its opposite end open, a secondary coil inductively coupled to said primary coil and having one end connected to the grounded filament circuit of the tube and 40 having its opposite end open, means for adjustably connecting said aerial to the primary coil and a metallic member associated with the primary coil and adjustable relatively to the secondary coil.

RICHARD H. BELL.
